James P. Morris,
Attorney

UNITED STATES PATENT OFFICE.

EDWIN CLEARY, OF LONDON, ENGLAND.

LIQUID VAPORIZER.

1,418,234.

Specification of Letters Patent. Patented May 30, 1922.

Application filed September 7, 1921. Serial No. 499,000.

To all whom it may concern:

Be it known that I, EDWIN CLEARY, a citizen of the United States of America, residing at London, England, have invented 5 new and useful Improvements in Liquid Vaporizers, of which the following is a specification.

This invention relates to apparatus for use in the vaporization and gasification of 10 liquids, and particularly to filters for use in connection with feeding such gas as vapor to a carburetor or the like.

Apparatus for this purpose is already known wherein the liquid to be vaporized 15 passes through superposed layers of wire gauze arranged in a tubular chamber having a plurality of inlet openings in the bottom, to which the liquid is supplied from a passage arranged at the side of the chamber, the vapour or gas generated being carried off from a central outlet arranged at the top of the chamber.

According to my invention, I employ a tubular vessel packed with wire gauze and 20 provided with a liquid inlet and a gas outlet, said vessel being arranged above a liquid fuel burner of the kind in which the liquid fuel is vaporized, the vapour mixed with air and burnt, preferably the burner 25 described in the specification of my former Letters Patent No. 1,381,080. The wire gauze may wholly fill the interior of the vessel, or it may partly fill it, e. g. a space 30 may be left at the bottom or end of the vessel, into which the liquid to be vaporized or gasified is delivered.

To my improved apparatus there is supplied either a liquid fuel which is to be 35 gasified or vaporized, or water which is to 40 be vaporized and superheated. The superheated gaseous fuel may be used in an internal combustion engine or for any other desired purpose, and the superheated steam 45 may be used as the working fluid for a steam engine, on an automobile or for any other desired purpose.

In one form of construction, the wire gauze layers are arranged in the form of discs or sheets provided with a perforation 50 to permit of their being threaded on to a rod on which they are held by means of nuts or the like. By this means the wire gauze can be very readily removed from or replaced in the tubular vessel, and the gauze 55 arranged to leave an empty space between it and the bottom of the tubular vessel as

above mentioned. The heater is arranged concentrically in front of the burner and is surrounded by a cylindrical casing, e. g. of steel lined with asbestos, of such internal diameter as to leave an annular space around the heater through which the flames from the burner can pass. This casing may advantageously be made continuous with the casing that encloses the nozzle and extended 60 heating conduit of such burner.

In the accompanying drawing, I have shown how my said invention may be conveniently and advantageously carried into practice. In this drawing, one form of the 70 improved gas generator is shown partly in vertical central section.

A is a tubular vessel, which may be advantageously formed of cast iron and be provided with a branch B at the bottom 75 of its lateral wall for the inlet of the liquid fuel or water to be gasified or vaporized. The vessel A is closed at the bottom and open at the top where it is provided with a screwed-on cover C having an outlet branch 80 D for the gas or the steam generated. For the purpose of filtering the gas or vapor there is tightly fitted into the interior of the vessel a series of superposed discs E, E of iron wire gauze, which have a central hole to 85 enable them to be threaded on to a screw threaded rod F, on which they are firmly held and are pressed together by means of nuts G, G. The tubular vessel and wire gauze may be made of other suitable metal, 90 e. g. nickel. The column of gauze so formed is continuous, each disc being in contact with another disc of the column throughout at least one of its surfaces, in this manner producing sinuous paths for the gas or vapor 95 which changes its direction at substantially every point. In addition to its function as a filter the column of gauze assists in the superheating of the gas or vapor, as will be hereinafter set forth.

The vessel A is provided with lateral lugs or projections H, H whereby it is secured by screws J, J in a double casing formed of concentric walls K, L, L' having asbestos or like packing M between them. The outer wall K 100 of this casing extends down to the base N of the apparatus, where it is provided with air-admission apertures O, O and forms the outer casing of the burner P, which is substantially of the form described in the specification of my Letters Patent No. 1,381,080. The outer wall K of the casing is provided 105 110 115

at the top with lugs Q, Q whereby it is drawn down on to the base N by means of bolts R, R. The liquid to be heated is conducted to the branch B through a pipe S, 5 the oil for the burner P being supplied through a pipe T. Moreover a suitable door K' is provided in the casing K to permit access to the burner P.

Since the lower part of the vessel A with 10 its gauze packing E, E is highly heated by the flame from the burner P the liquid fuel or other liquid to be vaporized and gasified is very rapidly and completely converted into gas or superheated steam in the case 15 where water is supplied to the inlet B.

In the case of vaporizing liquid fuel for 20 use in internal combustion engines, e. g. of an automobile, the fuel oil, e. g. kerosene or paraffin, is supplied to the vessel A through a feed pipe, which is preferably of small bore and is controlled by a suitable valve, the flow being promoted, e. g. by producing a suitable air pressure in the oil reservoir.

In the vessel A the gas or vapor is heated 25 by means of the heat supplied by the burner P, the gauze packing E acting as a conductor for the heat to distribute the same more uniformly throughout the vessel, and in this manner effecting a more thorough 30 and uniform preheating of the gas or vapor before being fed to the carburetor while at the same time filtering out any undesirable substances such as tar or the like.

What I claim is:—

35 1. An apparatus for use in vaporizing liquids comprising, a tubular vessel closed at both ends and having an inlet at the bottom

and an outlet at the top, packing within the vessel consisting of a plurality of centrally apertured wire gauze discs superposed one 40 upon the other with their surfaces held in contact one with another throughout the surfaces of the discs, a rod extending through the apertures in said discs, means for securing the superposed discs on the rod, 45 and a heat generator beneath said vessel.

2. An apparatus for use in vaporizing liquids comprising, a tubular vessel closed at both ends, packing within the vessel consisting of a plurality of centrally apertured 50 discs of wire fabric lying in superposed contacting relation one with another throughout their surfaces, a threaded rod extending through the apertures and nuts on said rod for holding said discs in contacting relation 55 and secured to said rod.

3. An apparatus for use in vaporizing liquids comprising, a tubular vessel closed at both ends, packing within the vessel consisting of a plurality of centrally apertured 60 discs lying in superposed contacting relation one with another throughout their surfaces, a threaded rod extending through the apertures and nuts on said rod for holding said discs in contacting relation and secured 65 to said rod, an inlet at the bottom and an outlet at the top of said vessel, a space at the bottom of the vessel beneath said discs, a radial inlet at the bottom of the vessel and an outlet at the top of the vessel.

EDWIN CLEARY.
